UNITED STATES PATENT OFFICE.

FREDERICK G. FOLBERTH, OF CLEVELAND, OHIO.

CARBURETER.

1,138,204.

Specification of Letters Patent.

Patented May 4, 1915.

Application filed August 4, 1911. Serial No. 642,309.

To all whom it may concern:

Be it known that I, FREDERICK G. FOLBERTH, a citizen of the United States, and resident of Cleveland, in the county of Cuyahoga and State of Ohio, have invented certain new and useful Improvements in Carbureters, of which the following is a specification.

The present invention relates to improvements in carbureters for hydrocarbon engines and in particular is an improvement upon the carbureter disclosed by my prior Patent No. 996,981 dated July 4, 1911.

In the accompanying drawings, Figure 1 is a vertical sectional view through a carbureter constructed in accordance with the invention. Fig. 2 is a horizontal section on the line 2—2 of Fig. 1, a portion of the casing being removed. Fig. 3 is a similar view 20 with one of the operating levers removed. Fig. 4 is a side elevation of the upper portion of the carbureter. Figs. 5 and 6 are detail views of portions of the valve-operating mechanism, the former showing the same in 25 different positions from that represented in Fig. 1. Fig. 7 is a detail view of a portion of the float chamber.

Referring to the drawings, 1 designates the mixing chamber of the carbureter which 30 is provided with a mixture outlet 2 controlled by a valve 3. Air is admitted to said chamber through a permanently open intake 4 and an auxiliary passage 5 controlled by an automatically-actuated valve 35 6. Hydrocarbon is supplied to said chamber 1 from a fuel inlet 7 controlled by a valve 8. The stem of this valve is guided in a suitable way in the casing of the carbureter and is normally held in closed position by the action of a coil spring 9.

In the normal operation of the apparatus the opening of the valve 8 is effected by a bifurcated lever 10 which is actuated by a lever 11 that rests upon the upper end of the 45 stem 6' of the automatically-controlled air intake valve 6. Connection between the levers 10 and 11 is afforded by an adjustable screw 12 mounted in the lever 10 and extending into contact with the lever 11. The 50 latter is fulcrumed upon suitable lugs rising from a plate 13 fitted in a groove or way in the top of the casing in such manner that it may be bodily adjusted in order to vary the effective length of such lever. 55 As shown the plate 13 is adapted to be thus actuated by means of a lever 14 to which is

connected a rod or link 15 adapted to be manually actuated. The lever 10 is provided at its free end with a projecting lip or tongue 10' which extends into a notch 8' 60 formed in the stem of the fuel valve 8, whereby when said lever is rocked about its fulcrum the valve will be positively lifted, the extent of opening of the fuel inlet 7 depending upon the adjustment of the lever 11 65 and connecting screw 12.

Spring-pressed plungers 10² depending from the lever 10 bear upon the plate 13 and act to hold it in its seat. It will be seen that by manipulation of such screw and adjustment of the lever 14 the extent of opening of the fuel inlet may be varied as desired.

Means are also provided whereby the levers 11, 10 may be actuated to open the fuel 75 inlet, while the automatically-controlled air intake valve 6 remains stationary. In the particular embodiment of the invention illustrated such means comprise a rock shaft 16, mounted in bearings in lugs 16' and to 80 said shaft is connected an arm 17 that extends beneath the free end of lever 11. By means of a rod or link 18 the shaft 16 may be rocked to adjust the parts from the position represented in Fig. 1 to those shown in 85 Fig. 5. A spring 20 connecting the casing or frame of the apparatus with an arm 19 on the shaft 16, to which the link 18 is attached, acts to retain said shaft and the arm 17 thereon in either of the positions 90 shown in Figs. 1 and 5.

A spring 21 acts to normally hold the air intake valve 6 in the position shown in Fig. 1, said spring surrounding the valve stem 6' and bearing against the body of the casing 95 and a piston-like head 22 attached to the lower end of said valve stem. Said head fits closely in a chamber 23 formed in the casing and communicating through a suitable duct with the float chamber 24, said parts forming a dash pot by which movement of the air valve is controlled.

The chamber 24 is provided with an inlet 25 adapted to be connected with a suitable hydrocarbon supply pipe or duct and communicates with the fuel inlet 7 of the mixture chamber through a duct 26. The valve 27 controlling the admission of hydrocarbon to the float chamber is guided in a plug 28 extending vertically through the float 110 chamber. A spring 29 acts to normally hold this valve in closed position, and the float

30 is adapted to actuate two levers 31 fulcrumed in suitable bearings in the plug 28 and engaging the stem of said valve, whereby the latter will be raised to admit hydrocarbon to the float chamber when the float therein has fallen to a predetermined extent. The compression of the spring 29 may be varied by means of an adjustable nut 32, a spring 33 being arranged between said nut 10 and the member 34 in which it is mounted. This spring, 33, acts as a lock to hold the members 32, 34, in the desired relation so that the tension or adjustment of the spring 29 will not be unintentionally changed. As 15 shown the top 35 of the float chamber is made of glass so that inspection of the interior thereof may be had at all times.

Means are provided whereby the supply valve 27 of the float chamber may be raised from its seat as desired independent of any movement of the float 30 or actuation of the levers 31. As shown such means comprise a lever 36 fulcrumed on a standard rising from the top of the float chamber and having one arm 37 engaging beneath a cap 38 at the outer end of the stem of said valve, the said lever 36 being provided with a suitable draft connection, by means of which it may be manually rocked as desired. A 20 spring 39 acts to normally retain said lever 36 in the position shown in Fig. 1.

Means are provided whereby any sediment contained in the hydrocarbon supply to the float chamber will be prevented from 25 passing to the interior thereof and can be readily removed. As shown the plug 28 is provided with an annular groove 40 which is in alignment with the supply passage 25 and within which is arranged a suitable 30 screen 41. Said passage 40 communicates with the seat or passage closed by the valve 27 through passages 42 and also on the opposite side of the screen 41 with a vertical recess or sediment chamber 43 formed in the 35 lower end of said plug. Access to this sediment chamber is had through a port controlled by a screw plug 44.

The operation and advantages of the apparatus hereinbefore described will be 40 readily understood. It will be seen that by adjustment of the screw 12 the lip or projection 10' on the lever 10 may be adjusted in the notch in the valve stem 8' to vary the distance which such lever must be moved before it positively engages with the valve 45 stem, and by adjustment of the lever 14 the effective length of the lever 11, which is directly actuated by the automatically-controlled air intake valve, is varied so that the proportional opening of the fuel inlet with 50 relation to the air supply can be varied as desired. The several levers and connections between the automatically-controlled air valve and the fuel inlet valve may be covered 55 and protected by a cover 45, which is held

in place by a resilient arm 46 secured to the casing at one end by a screw 47 about which it may be turned when it is desired to remove the cover 45.

Having thus described the invention what 70 is claimed as new is:

1. In a carbureter, the combination with a casing having an air intake and a float chamber, of an automatically-controlled air intake valve, a lever adapted to be actuated by 75 said air valve, a fuel valve, and a second independently fulcrumed lever engaging the fuel valve and adapted to be actuated by the first said lever.

2. In a carbureter, the combination with a 80 casing having an air intake and a float chamber, of an automatically-controlled air intake valve, a fuel valve, a lever adapted to be actuated by said air valve and bodily adjustable to vary the distance between its 85 fulcrum and the point of engagement with the air valve, and an independently fulcrumed lever connected with the fuel valve and adapted to be actuated by the first said lever.

3. In a carbureter, the combination with a 90 casing having an air intake and a fuel inlet, of an automatically-controlled air intake valve, a fuel valve, two levers, one adapted to be actuated by said air valve to rock the 95 other and the latter engaging the fuel valve, and means for varying the relation between said levers, for the purpose described.

4. In a carbureter, the combination with a 100 casing having an air intake and a fuel inlet, of an automatically-controlled air intake valve, a fuel valve, a lever adapted to be actuated by said air valve, means for shifting said lever bodily relative to the air valve to vary the effective length of the lever, a 105 second lever adapted to actuate the fuel valve, and an adjustable connection between said levers.

5. In a carbureter, the combination with a 110 casing having an air intake and a fuel inlet, of an automatically-controlled air intake valve, a fuel valve, a lever adapted to be actuated by said air valve, means for shifting said lever bodily relative to the air valve to vary the effective length of the 115 lever, a second lever adapted to actuate the fuel valve, and a stud or pin adjustably connected with one of said levers and extending into contact with the other.

6. In a carbureter, the combination with 120 a casing having an air intake and a fuel inlet, of an automatically-controlled air intake valve, a fuel valve, a lever adapted to open the fuel valve, means for rocking said lever including a second lever adapted to be 125 actuated by the air valve, and means for rocking the last said lever independent of movement of the air valve.

7. In a carbureter, the combination with a 130 casing having an air intake and a fuel in-

let, of an automatically-controlled air intake valve, a fuel valve, two independently fulcrumed levers, one engaging at its free end with the fuel valve and the other adapted to be actuated by the automatically-controlled air valve, and an adjustable connection between said levers.

8. In a carbureter, the combination with a casing having an air intake and a fuel inlet, of an automatically-controlled air intake valve, a fuel valve, two independently fulcrumed levers, one engaging at its free end with the fuel valve and the other adapted to be actuated by the automatically-controlled air valve, a connection between said levers, and means for bodily shifting one of said levers to vary its effective length.

9. In a carbureter, the combination with a casing having an air intake and a float chamber, of an automatically-controlled air intake valve, a lever adapted to be actuated by said air valve, a fuel valve, and a second lever engaging the fuel valve and extending substantially parallel to and adapted to be actuated by the first said lever.

10. In a carbureter, the combination with a casing having an air intake and a float chamber, of an automatically-controlled air intake valve, a lever adapted to be actuated by said air valve, a fuel valve, a second lever fulcrumed beyond the free end of the first said lever and engaging the fuel valve, and an adjustable contact between the levers.

11. In a carbureter, the combination with a casing having an air intake and a fuel inlet, of an automatically controlled air intake valve, a fuel valve, a lever adapted to be actuated by the air valve, means operable by said lever for opening the fuel valve, and means for rocking said lever independent of movement of the air valve.

12. In a carbureter, the combination with a casing having an air intake and a fuel inlet, of an automatically controlled air intake valve, a fuel valve, two superposed levers, one engaging the fuel valve and the other adapted to be actuated by the air intake valve, an adjustable contact between said levers, and means for rocking the levers independent of movement of the air intake valve.

13. In a carbureter, the combination with a casing having an air intake and a fuel inlet, of an automatically controlled air intake valve, a fuel valve, two levers, one adapted to be actuated by said air valve to rock the other and the latter engaging the fuel valve, and means for shifting one of said levers bodily to vary the relative movements of the valves.

In testimony whereof I affix my signature in presence of two witnesses.

FREDERICK G. FOLBERTH.
